UNITED STATES PATENT OFFICE.

THOMAS J. HOUCK, OF BALTIMORE, MARYLAND, ASSIGNOR OF ONE-HALF TO
JOHN T. WOOD, OF SAME PLACE.

ELECTRIC COMMUNICATION WITH RAILWAY-TRAINS.

SPECIFICATION forming part of Letters Patent No. 428,562, dated May 20, 1890.

Application filed November 6, 1889. Serial No. 329,432. (No model.)

To all whom it may concern:

Be it known that I, THOMAS J. HOUCK, a citizen of the United States, residing at Baltimore, in the State of Maryland, have invented certain new and useful Improvements in Electric Communication with Railway-Trains, of which the following is a specification.

This invention relates to means for sending electric currents to and from moving railroad-trains, so as to afford communication between a station and any one or the whole number of moving locomotives, or between two or more moving locomotives.

15 The object of the invention is to provide a railroad with means for telephonic or telegraphic communication between terminal stations and any one or all the moving locomotives distributed along the road between the said terminal stations.

By this invention a "block system" may be arranged and operated on a railway without employing signal men at stations along the road.

25 The invention is illustrated in the accompanying drawings, in which—

Figure 1 is an elevation or side view of a railroad-track, locomotive, two stations, and the connecting line-wires arranged according 30 to my invention. The entire view shown by the two broken sections on Sheet 1 are to be considered together as one figure. Fig. 2 is a view showing part of a locomotive provided with a telephone, the three connecting line-wires, an electro-magneto circuit-closer connected by tap-wires with one of said line-wires and the wires of another circuit to operate the magneto circuit-closer. Fig. 3 shows a station and telephone, the three connecting line-wires, an electro-magneto circuit-closer, and tap-wires, a battery, the wires, and a switch-board for operating all the magneto circuit-closers.

The letter A designates the station at one 45 end of the road, and A' the station at the other end. A telephone B, or in its stead a telegraphic transmitter and receiver, is at each terminal station.

The letter C designates the railway-track. 50 Three wires in all are used in the circuit employed for communication. In the present

instance these wires are shown suspended on poles d. The particular manner of running the wires is immaterial. One wire (designated by the letter a) runs direct without break 55 from one telephone B to the other. The second wire b runs from a switch-point f near one telephone to a switch-point f near the other telephone, but is broken by an insulator e, inserted in the wire at the end of every 60 other section or block, which sections or blocks are designated by the figures 1, 2, 3, 4, 5, and 6. The third wire c has its ends made fast to the initial posts d at each terminal station, and this wire is broken by an insulator e', inserted in the wire at the end of alternate sections. Thus each section or block, after the first and last one, is marked at one end by an insulator e on the second wire b and at the other end by an insulator e' on the third 70 wire c.

At each end of the sections or blocks is an electro-magneto circuit-closer, of which seven are shown in the present instance, designated D', D², D³, D⁴, D⁵, D⁶, and D⁷. The second or 75 third wires b c, as the case may be, are connected at opposite sides of their insulators e e' by tap-wires g g' with said electro-magneto circuit-closers. The tap-wires g² g³ connecting the magneto circuit-closer at the terminal stations are differently connected—that is, one tap-wire g² is attached to the second wire b and the other g³ is attached to the third wire c.

The electro-magneto circuit-closers consist 85 of an electro-magnet h and a bar i, attracted by said magnet and attached to a non-conductive shaft j, which is movable in a bearing k, and carries a T-shaped circuit-closer l. At each side of the circuit-closer is a contact-plate m, to which the tap-wires are attached. It will be seen that when the magnet h is energized it will attract the bar i, and thereby the T-shaped circuit-closer l is brought 90 against the contact-plates m, which completes the line-wire circuit. Normally the electro-magnets h are in a demagnetized condition, and consequently the line-wire circuit is broken.

For the purpose of operating the electro-magneto circuit-closers I employ a battery N, located at one terminal station, a wire o,

leading from one pole of the battery to the electro-magnet h at the other terminal station, and branch wires o' , leading from said wire o to each of the other magnets h . From each 5 magnet another wire p leads back to the other pole of the battery; but this wire has a switch in its line for opening and closing the circuit. In the present instance all these switches are arranged on a board at one terminal station, and are designated q' , q^2 , q^3 , q^4 , q^5 , q^6 , 10 and q^7 , corresponding to the magnets D' , D^2 , &c.

Adjoining each telephone B , at the terminal stations, is a grounded wire r , connected 15 with a switch-point f' , and a switch s is attached to a wire leading to one side of the telephone and in the position to make contact with either of the two switch-points $f f'$.

Each locomotive-cab E is provided with a 20 telephone B' , two switches t t' , both connected with the telephone, and two points for connection with each switch. Each locomotive also has an upward-projecting arm F , carrying three contact-trolleys a' , b' , and c' , which 25 traverse the line-wires. From each trolley a wire leads to a switch-point in the cab, as follows: From the trolley a' a wire leads to the switch-point u , and from the trolley c' a wire leads to the switch-point u' . From the trolley 30 b' a wire leads to the switch-point v , and from the switch-point v' a wire r' leads to the axle or other suitable part of the locomotive to make a ground-connection.

It will be the duty of the operator at the 35 terminal station, where the switch-board is, to open or close the switches which are necessary to maintain communication with those sections or "blocks" of the road which are occupied by trains or locomotives.

40 In the operation of the invention, when it is desired to communicate between a terminal station and the various locomotives on the road, the following condition of parts should exist: First of all it is necessary that the 45 switches at the telephones at the terminal stations shall be set as shown—that is, to connect with the switch-point to which the second wire b is attached—thereby making provision for a metallic circuit through the three 50 wires a b c . It is also necessary for the locomotive engineers when running on the road to have the switches in their cabs maintain the position shown in Fig. 2—that is, the switch t to be in contact with the point u' 55 and the switch t' to be in contact with the point v . Suppose, as in the present case, the locomotive is in section or block two. This location of the locomotive of course will be known to the operators at the terminal stations, they having been notified by the engineer, through the telephone B' in his cab, just previous to his leaving the last section or block. The operator will have the switches q' , q^4 , and q^6 set to close the circuit, and the 60 engineer will have the switches in his cab set as already explained. Under these conditions the terminal telephones B and the loco-

motive-telephones B' will be in communication. For the purpose just described the line-wires a b c are used as a metallic circuit 70 and the grounded wires r , adjoining the telephones B , are not employed. My invention, therefore, does not necessarily include said grounded wires as an essential part.

When it is desired to communicate from 75 one of the terminal stations to a locomotive occupying any one particular section or block without including the locomotives in other sections, the engineer will be instructed to establish a ground-circuit by moving the cab-switches t t' , so that the switch t will make contact with the point u , and the switch t' with the point v' . The station-operator will place the switch s in contact with the point f' , thereby establishing a grounded circuit. 80 85

Where the term "instrument," or "electric receiving and transmitting instrument" is employed in the claims, I mean to include either a telephone or telegraphic instrument. Where the term "locomotive," or "car," or "train" 90 is employed, either and all of these are meant to be included. It will be obvious that intermediate stations along the road may have instruments connected with the line-wires in the same manner.

95 By the manner here described of arranging the line-wires, insulators, electro-magneto circuit-closers, and tap-wires each and every instrument at terminal stations, and also those distributed along the road, either 100 in locomotive-cabs or at intermediate stations, are connected in series by a metallic circuit, and in the case of using telephones this arrangement very largely obviates induction.

Having described my invention, I claim— 105

1. In a system of electric communication with moving railway-trains, the combination of an electric circuit consisting of three parallel line-wires a b c , the first one a of which is without break, the second one b being broken by insulators e , inserted at intervals along its length, and the third one c also broken by insulators e' , inserted at intervals along its length, the said intervals and insulators of the two wires alternating with respect to each other, an electro-magneto circuit-closer for each of said inserted insulators, two tap-wires connecting each electro-magneto circuit-closer with one or the other of said insulator-inserted wires, each tap-wire 115 taking on a different side of the insulator, a railroad-track, a terminal station having an electric receiving or transmitting instrument, and a locomotive or car provided with an electric receiving or transmitting instrument, and also provided with an arm having contact-trolleys to take on the line-wires. 120 125

2. A system of electric communication with moving railway-trains, consisting of the combination of the following: a railroad-track, the two terminal stations, each having an instrument, a circuit between said terminal stations consisting of three wires, as follows: the first wire a connecting the said two instruments 130

and without break, the second wire *b* extended between and connected with said two instruments but broken by an inserted insulator *e* at intervals along its length, and the 5 third wire *c* extended between the terminal stations, but unconnected with either of said two instruments, and broken by an inserted insulator *e'* at intervals, which alternate with those of the second wire, an electro-magneto 10 circuit-closer for each of said wire-inserted insulators, two tap-wires connecting each electro-magneto circuit-closer with either the said second or third wires (as the case may be) at opposite sides of said inserted insulators, and 15 a locomotive or car provided with an electric receiving or transmitting instrument.

3. In a system of electric communication with moving railway-trains, the combination of an electric circuit consisting of three parallel line-wires *a b c*, the first one *a* of which is without break, the second one *b* being broken by insulators *e*, inserted at intervals along its length, and the third one *c* also broken by insulators *e'*, inserted at intervals 20 along its length, the said intervals and insulators of the two wires alternating with respect to each other, an electro-magneto circuit-closer for each of said wire-inserted insulators, two tap-wires connecting each electro-magneto circuit-closer with one or the other of said insulator-inserted wires, each 25 tap-wire taking on a different side of the insulator, a telephone or telegraphic instrument at each end of the circuit, a grounded wire *r*, connected with a switch-point *f'*, adjoining each telephone, a switch *s*, attached 30 to one of the wires of the metallic circuit near the telephone and in position to make contact with the said point of the grounded wire, a locomotive or car provided with a telephone or telegraphic instrument having electrical 35 connection with said metallic circuit, and a wire *r'* on the locomotive or car to make a ground-connection.

In testimony whereof I affix my signature in the presence of two witnesses.

THOMAS J. HOUCK.

4. In a system of electric communication with moving railway-trains, the combination of a railroad-track, a metallic circuit consisting of three parallel line-wires *a b c*, the first one *a* of which is without break, the second one *b* being broken by insulators *e*, inserted at intervals along its length, and the third one *c* also broken by insulators *e'*, inserted at intervals along its length, the said intervals and insulators of the two wires alternating with respect to each other, an electro-magneto circuit-closer for each of said inserted insulators, two tap-wires connecting each electro-magneto circuit-closer with one or the other of said insulator-inserted wires, each 40 tap-wire taking on a different side of the insulator, a telephone or telegraphic instrument at each end of the circuit, a grounded wire *r*, connected with a switch-point *f'*, adjoining each telephone, a switch *s*, attached 45 to one of the wires of the metallic circuit near the telephone and in position to make contact with the said point of the grounded wire, a locomotive or car provided with a telephone or telegraphic instrument having electrical 50 connection with said metallic circuit, and a wire *r'* on the locomotive or car to make a ground-connection.
